UNITED STATES PATENT OFFICE.

ROBERT C. COLE, OF HARTFORD, CONNECTICUT, ASSIGNOR TO THE JOHNS-PRATT COMPANY, OF HARTFORD, CONNECTICUT, A CORPORATION OF CONNECTICUT.

PROTECTED ELECTRIC-SERVICE CUT-OUT.

1,158,896.

Specification of Letters Patent.

Patented Nov. 2, 1915.

Application filed October 23, 1914. Serial No. 868,571.

To all whom it may concern:

Be it known that I, ROBERT C. COLE, a citizen of the United States, residing at Hartford, in the county of Hartford and 5 State of Connecticut, have invented a new and useful Improvement in Protected Electric-Service Cut-Outs, of which the following is a specification.

This invention relates to that class of cut-outs for electric service which are more especially designed for use in main lines where they enter buildings. These cut-outs are commonly inclosed in boxes and provided with fuses so arranged that the fuses 10 cannot be reached without opening the boxes, and the boxes cannot be opened without breaking the circuits.

The object of the invention is to provide a simple, cheap and compact cut-out of this 15 nature which is efficient, safe and easily manipulated.

Figure 1 of the accompanying drawings shows a vertical section of the structure, with the box, cover and block in the cover 20 cut on the plane indicated by the dotted line 1—1 on Fig. 2. Fig. 2 shows a plan of the device with the cover removed. Fig. 3 shows a vertical section of the box and cover on the plane indicated by the dotted line 25 3—3 on Fig. 2. Fig. 4 is a view looking into the cover of the box.

The box 1 is desirably made of cast iron or steel with one or more openings, depending on the number of wires in the installation 30 with which the cut-out is to be used, in opposite sides. In these openings are insulating bushings 2. On one side of the box are ears 3 to which are hinged the ears 4 that project from the cover 5. On the opposite 35 side of the box are lugs 6 between which is pivoted a bolt 7 that carries a nut 8 and is adapted to be turned up into engagement with wings 9 on the cover for the purpose of holding the cover fastened down to the box.

To the bottom, inside of the box, a block 40 10, desirably of porcelain, is secured. This block has one or more conducting plates 11 in its upper face along two opposite sides. To the outer end of each of these plates a 45 wire lug 12 is fastened. Projecting upwardly from the inner end of each of the

plates are fingers 13 shaped to form switch clips.

To the inside of the cover an insulating block 14, preferably made of porcelain, with 55 downwardly opening pockets 15, is fastened. On two opposite sides of the block in the cover and downwardly projecting blades 16 which, when the cover is closed, are adapted to extend between and engage with the 60 spring fingers which form the switch clips on the base. In the pockets are metallic screw threaded shells 17, each of which is connected by a plate 18 with a blade on one side of the block in the cover. In the center 65 of each of the shells and insulated therefrom is a contact 19 having a stem 20 which extends upwardly through the block and engages a conducting plate 21 which is connected with the switch blade on the other 70 side of the block. These shells are arranged to receive the common form of fuse plug 22.

Owing to the construction the service 75 wires may be brought into the bottom or top of these boxes, depending upon the arrangement of the circuit wires in the locality in which the boxes are to be used. They are compact and safe. The fuses cannot be reached without opening the cover and the cover cannot be opened without breaking the 80 circuit. The circuit is thoroughly protected by the fuses, and the switch blades and clips, being permanently located and independent of the fuses, will at all times properly engage to render efficient service without danger of heating or becoming dislocated so as 85 to fail to connect.

The invention claimed is;

A cut-out consisting of a metallic box, a cover hinged at one edge and adapted to be 90 secured to the other edge of the box, an insulating block with recesses in its upper face fastened to the inside of the bottom of the box, an insulating block attached to the cover and swinging therewith, conducting 95 plates secured to the top of the block in the box along opposite edges, means for connecting wires to said plates, switch clips projecting upwardly from said plates, switch blades secured to and projecting downwardly from the underside along opposite edges of the block on the cover in position 100

to engage with said clips, a plurality of insulating sockets extending downwardly from the block on the cover, a threaded shell secured in each of the sockets, conductors connecting said shells to the switch blades on one side, central terminals in said sockets, conductors connecting said terminals to the switch blades on the other side,

and fuse plugs screwed into said shells and extending downwardly therefrom into the 10 recesses in the block in the base.

ROBERT C. COLE.
